UNITED STATES PATENT OFFICE.

WILLIAM H. YOUNG, OF MILLVALE BOROUGH, PENNSYLVANIA,
ASSIGNOR OF ONE-HALF TO A. K. LYON, OF MILLVALE BOROUGH, PENNSYLVANIA.

NON-REFILLABLE BOTTLE.

No. 825,602.

Specification of Letters Patent.

Patented July 10, 1906.

Application filed January 11, 1906. Serial No. 285,532.

To all whom it may concern:

Be it known that I, WILLIAM H. YOUNG, a citizen of the United States, residing at Millvale borough, in the county of Allegheny and State of Pennsylvania, have invented 5 certain new and useful Improvements in Non-Refillable Bottles; and I do declare the following to be a full, clear, and exact description of the invention, such as will enable 10 others skilled in the art to which it appertains to make and use the same, reference being had to the accompanying drawings, and to the figures of reference marked thereon, which form a part of this specification.

15 This invention relates to an improved non-refillable bottle; and it comprises a stopper formed in two sections, the one analogous with the other and adapted to be fitted into the neck of the bottle, a tortuous or zigzag 20 passage extending through said stopper, a valve located in the base of said passage, and a means for locking said stopper in the neck of the bottle, together with the certain other details of construction as will be fully de- 25 scribed hereinafter.

In the accompanying drawings, Figure 1 is a side sectional elevation of the neck of an ordinary bottle, the said neck being formed with an inner peripheral groove to engage 30 with a means for locking the stopper therein, one of the sections of which is shown in position. Fig. 2 is a perspective view of one of the sections of the stopper. Fig. 3 is a sectional plan view taken through the stopper 35 on the line X X of Fig. 1, showing the manner in which the valve is hinged in position. Fig. 4 is a perspective view of the said valve detached from the stopper. Fig. 5 is a perspective view, somewhat enlarged, of the 40 spring for locking the stopper in the neck of the bottle. Fig. 6 is a side elevation of a portion of one of the sections of the stopper, showing the valve in open position.

To put my invention into practice, and 45 thereby provide a bottle that cannot be refilled or the stopper removed therefrom when once properly inserted, I form within the neck 2 of the bottle 1 at a suitable position a circumferential groove 19 as a part of 50 the means employed for locking the stopper to prevent its removal when once inserted. This stopper comprises two semicylindrical tapering sections 3 and 3', the one analogous

with the other, the outer diameter of which corresponds to and is made to fit neatly and 55 tightly within the neck 2 of the bottle. Formed in the outer surface of each of these sections 3 and 3' of the stopper are recesses 13, located opposite the groove 19 when the stopper is in position in the neck of the bottle, the one portion of each recess registering with the other of the second section of 60 said stopper in such manner that a flat bent spring 15 (see Figs. 1 and 5) will engage with the two sections of the stopper at the same 65 time. This spring 15 is doubled back upon itself to form a leaf 17 to engage with the groove 19 in the bottle-neck and with a portion 70 16 at right angles to enter a notch 14 in the stopper 3 3'. Formed in each section 70 3 and 3' of the stopper is a tortuous passage, the top entrance 4 of which is located at one side of the center, the passage first extending to the left and then turned to the right by intermediate baffle-walls 6. Then by op- 75 positely-extending baffle-walls 7 on the one side and a third baffle-wall 8 the passage is continued first to the right and then to the left and thence downward to a valve- 80 chamber in which a valve-seat 10 is formed. These baffle-walls are formed out of line the 85 one with the other, the upper projecting beyond the lower in such manner that a wire or other instrument cannot be forced down the passage to hold the valve open. This valve consists of a piece of glass or other 90 suitable material 11, having a flat base and outwardly-projecting hinge portions 12, which latter enter recesses formed in the valve-chamber of the stopper, as will be best 95 seen at Fig. 3 of the drawings. In practice these stoppers above described are formed by the aid of suitable molds, and preferably of glass, and are arranged in pairs, the outer surface of which may be ground into the neck of the bottle to insure a tight and perfect fit.

To arrange the stopper in position after the bottle has been filled, the two sections of the stopper are placed together, having first 100 arranged the valve 11 in its place. One or more springs are inserted in the recesses 13, the short ends 16 of which are forced into the notches 14, and the whole carefully inserted in the neck 2 of the bottle. The stopper is 105 now forced downward until the spring-leaf

17 passes the shoulder of the circumferential groove 19 and permitted to spring outward, thereby effectually locking the stopper in the neck of the bottle. An ordinary cork 5 20 is now inserted above the stopper to prevent leakage.

It will be readily seen by the above description, taken in connection with the several views of the drawings, that the contents 10 of the bottle may be easily removed by simply pouring in the usual manner and by the peculiar construction of the passage an instrument cannot be inserted to engage with the valve 11 and hold the same open to refill 15 the bottle. Should a wire be inserted for this purpose, the same might be passed beyond the baffle-wall 7 and the point would meet the inclined top surface of the wall 8 and guide the end of said wire into the angle 20 formed thereby or engage with the top of the open valve to close the same.

Various slight modifications and changes may be made in the details of construction without departing from the spirit of the in-

vention. Therefore I do not wish to confine 25 myself to the exact construction shown and described, but wish to claim all such modified forms as would come properly within the general scope of the invention.

Having thus described my invention, what 30 I claim, and desire to secure by Letters Patent, is—

A bottle-stopper comprising a body portion adapted to be fitted and locked in the neck of a bottle, said stopper being formed 35 with a tortuous passage, baffle-walls within said passage, the lower wall of which forming an acute angular pocket and located to permit a valve when open to project some distance above its top surface, and a valve 40 hinged in the lower end of the tortuous passage, as described.

In testimony whereof I affix my signature in presence of two witnesses.

WILLIAM H. YOUNG.
